DOOR LOCK

Walter E. Schlage, Burlingame, Calif., assignor to
 Schlage Lock Company, San Francisco, Calif.,
 a corporation of California

Application April 30, 1941, Serial No. 391,024

12 Claims. (Cl. 292—169)

This invention relates to door locks of the type disclosed in my co-pending application, entitled "Door lock," filed April 21, 1941, Serial No. 389,512, and especially to a lock of this character which employs a single spindle.

In the door lock disclosed in my co-pending application above referred to, two latch bolts are disclosed which are referred to as the main and the secondary latch bolts, and both or either of them may assume a projected or a retracted position. Each latch bolt is attached to a retractor plate, and these plates are actuated by rollback members formed on an inner and an outer spindle. Within these spindles is mounted an actuator which controls the position of the secondary latch bolt, and also a dogging member whereby the outer spindle is dogged against operation when the secondary latch bolt is fully projected. This actuator is controlled by a key mechanism disposed in the outer spindle, and it is also controlled by a longitudinally movable member manually operated by a pushbutton mounted in the inner spindle.

The object of the present invention is to provide a door lock having a main and a secondary latch bolt, both or either of which may assume a projected or retracted position; to provide a door lock in which the latch bolts are attached to individual retractor plates which, in this instance, are actuated by a rollback member formed on the single spindle; to provide an actuator within the spindle which controls the position of the secondary latch bolt; to provide key actuated means in the outer end of the single spindle for rotating said member, and manually operated means in the inner end of the spindle which is also rotatable to control the position of the actuator; to provide means on the retractor plate which carries the secondary latch bolt for dogging the spindle against rotation when the secondary latch bolt assumes its full projected position; to provide means whereby the key actuated means or the manually actuated member in the inner end of the spindle will dog or undog the spindle and restore the secondary latch bolt to a retracted position; to provide a secondary latch bolt which, when fully extended can not be depressed by engagement with the striker plate of a door; and further, to provide a main and a secondary latch bolt which telescope with relation to each other, so that one may form a guard for the other.

The invention is shown by way of illustration in the accompanying drawings, in which

Fig. 1 is a horizontal longitudinal section taken on line I—I of Fig. 2, said view showing the main

latch bolt in normal projected position, the secondary bolt in retracted position, and the single spindle and the knob secured thereto in undogged position;

5 Fig. 2 is a vertical longitudinal section taken on line II—II of Fig. 1;

Fig. 3 is a section similar to Fig. 1, showing both latch bolts fully projected and the single spindle and the knob secured thereto in dogged position;

Fig. 4 is a perspective view of the retractor plate which carries the secondary latch bolt;

Fig. 5 is a perspective view of the retractor plate which carries the main latch bolt;

Fig. 6 is a perspective view of the key actuated tumbler cylinder;

Fig. 7 is a perspective view of the actuator which controls the position of the secondary latch bolt and the dogging member; and

20 Fig. 8 is a perspective view of the single spindle.

Referring to the drawings in detail, and particularly to Figs. 1 to 3 inclusive, A indicates a portion of a door to which is suitably secured a lock housing consisting of two side plates 2 and 3,

25 which are joined at their outer ends by a face plate 4. Secured between the plates 2 and 3 of the lock housing is a U-shaped frame consisting of upper and lower horizontally extending arms 5 and 6 which are connected at the rear ends by

30 an end bar 7. The forward ends are provided with right-angularly bent lugs 8—8, and they are secured to the face plate 4 by rivets, counter-sunk screws or the like, such as indicated at 9.

Two latch bolts are employed, one of which is indicated at B and which will hereinafter be referred to as the main latch bolt, and the other indicated at C, which will hereinafter be referred to as the secondary latch bolt. The main latch bolt is best shown in Figs. 1 and 5. It is attached

40 to a retractor plate generally indicated at b. This plate is rectangular in shape and has two projecting edges 10—10 which extend into guide slots 11—11 formed in the arms 5 and 6 of the U-shaped frame. An elongated opening 12 is formed

45 in the plate, and rearwardly thereof, a head member 14 which is notched as at 15 to straddle a bar which will hereinafter be referred to as the actuator. Also the head is notched to form a pair of shoulders 16—16 which are adapted to be engaged by a rollback member hereinafter to be described.

The secondary latch bolt C is similarly attached to or formed as an integral part of a rectangular-shaped retractor plate generally indicated at c. This plate has projecting edges 10a

extending into the guide slots 11-11 formed in the arms 5 and 6, heretofore referred to. The plate also has an elongated opening 12a formed therein, rearwardly of which is a head 14a. This presents a face 16a adapted to be engaged either by the rollback member or the actuator heretofore referred to. The head also carries a dogging lug 17 and a spring seat 18a, a similar seat 18 being formed on the head 14 of the other retractor plate.

The latch bolt C consists of a plate 19 and a pair of right-angularly bent portions 20-20 which form a guide and a guard for the latch bolt B, as will hereinafter be described.

Formed on the side plates 2 and 3 of the lock housing are outwardly extending bearing hubs 21 and 22, in which is journaled a spindle generally indicated at D. This spindle is best shown in Figs. 1, 3 and 8. A central portion indicated at 23 is enlarged in diameter, while the inner and outer ends of the spindle are reduced in diameter, as indicated at 24. The central enlarged portion is cross-slotted as at 25, and a rollback member 26 is thus formed. The opposite sides of the cross slot are notched as shown at 27, and one or the other of these notches is provided for the reception of the dogging member 17. In as much as there is only one dog 17 formed on the retractor plate c, only one of the notches 27 would be required, but two are preferably employed, as this allows for both right-hand and left-hand installations.

A pair of knobs 30 and 31 are secured in any suitable manner on the opposite ends of the spindle. The knob 30 will hereinafter be referred to as the outer knob, and the knob 31 as the inner knob. Insertible through the inner end of the spindle is a bar 32 which is circular in cross section and snugly fits the interior of the spindle, which is tubular. A collar 33 is formed on the outer end of said bar and engages the end of the spindle. This collar is overlaid by an annular shoulder 34 of the knob, and the bar is thus secured against endwise movement within the spindle, but it is free to rotate, and means in the form of a turnpiece 35 is formed on the outer end of the bar and projects beyond the face of the knob 31 to permit it to be grasped so as to rotate the bar. The bar is best shown in Figs. 1, 3 and 7. Adjacent its inner end it is cross slotted to form a flat face 36 and a half-round or semi-circular rounded portion 36a, which will hereinafter be referred to as the actuator. Beyond that is a cylindrical extension 37, and on the end thereof is formed a lug 38 which terminates in a pin 38a.

Extending through the outer knob 30 and into the tubular spindle is a key actuated tumbler cylinder 39 (see Figs. 1, 3 and 6). The spindle proper functions as a housing for the cylinder and the tumblers 40 normally project into a slot 41 formed in the spindle, and thus secure the cylinder against rotation within the spindle. However, by inserting a key, the tumblers 40 are retracted and the cylinder is then free to rotate and when it is rotated a lug 42 formed on the inner end engages the lug 38 of the actuator and rotation is thereby imparted to the actuator by the key actuated cylinder. The pin 38a on the actuator extends into a recess 38b formed in the end of the key actuated tumbler cylinder 39. This is desirable, as it centralizes the bar 32 with relation to the tumbler cylinder 39 and furthermore prevents improper application or rotational movement between the lugs 38 and 42. The key

actuated tumbler cylinder has a collar 45 formed on its outer end, and this is overlaid by an annular shoulder 46 formed on the knob 30. The key cylinder is thus secured against endwise movement but is free to rotate within the spindle when a key is inserted.

The normal position of the mechanism is that shown in Fig. 1. In this position the main latch bolt B will be projected and the secondary latch bolt will assume a retracted position, and as the dog 17 is carried by the latch plate c the dog will assume a position rearwardly of the spindle and the notches 27 formed therein. Thus the spindle may be rotated by either of the knobs and when it is rotated the rollback member 26 will engage one or another of the shoulders 16 formed on the retractor plate b, and this retractor plate will thus be forced inwardly within the lock housing against the pressure of a spring 50, and as the retractor plate b moves inwardly the main latch bolt B attached thereto will be retracted, and the door may be opened, and when the knob which was previously rotated to rotate the spindle is released, a spring 50 will force the retractor plate back to normal extended position so as to extend the bolt B, and the spindle and knobs will obviously return to normal position and be held in that position by the shoulders 16 engaging the face of the rollback member.

If a person is in a room and desires to lock the door against intruders, it is only necessary for that person to grasp the turnpiece 35 and rotate the bar 32 so that the actuator 36 moves from the position shown in Fig. 1 to the position shown in Fig. 3. This requires a half revolution of the turnpiece, and it permits the retractor plate c to follow and to drop into the cross slot formed in front of the actuator. This position of the secondary retractor plate is shown in Fig. 4. It is urged to that position by a spring 51, and it will remain in that position until the actuator is re-rotated a half revolution either by the turnpiece 35 or by the key actuated mechanism hereinafter to be described. When the secondary latch bolt C is projected, it will assume the position shown in Fig. 3. In this position it functions as a bolt which can not be jimmied, as no beveled face is presented. Furthermore, it functions as a guide and as a guard for the main latch bolt B, and as the secondary latch bolt is made of a hard steel, even sawing of the latch bolt can be prevented.

When the door has been locked as by rotation of the turnpiece 35, it is triple locked; that is, it is double locked by the two bolts being extended, and it is triple locked as the dog 17 will in this position enter one of the notches 27 and thus dog the spindle against rotation or, in other words, render it inoperative, as it can not be rotated by either knob. Hence, if it is desired to unlock the door, it can be accomplished from the inside by grasping the turnpiece 35 and rotating the bar 32 until the actuator assumes the position shown in Fig. 1, or it may be accomplished from the outside by a person having the proper key. That is, insertion of the key will retract the tumblers 40 and permit the cylinder 39 to be rotated, and when it is rotated, it will transmit rotary motion to the actuator through means of the lugs 42 and 38. The revolution would be a half revolution so as to bring the actuator back to the position shown in Fig. 1. Hence whether the actuator is rotated by the key mechanism or by the turnpiece 35 it may be rotated by either member to assume either the position shown in

Fig. 1 or that shown in Fig. 3. The actuator 38 controls the position of the retractor plate c and the secondary latch bolt C and the dogging member 17 at all times. In the position of the actuator shown in Figs. 1 and 2 the actuator engages the face 16a of the retractor plate c and thereby holds this plate in its innermost position. By rotating the bar 32 either by the turnpiece or the key mechanism the actuator 38 will assume a position opposite from that shown in Fig. 1 or Fig. 2, or in other words, the position shown in Fig. 3. In that position the face 16a of the retractor plate c will still engage the actuator, but the retractor plate c and the secondary latch bolt C will assume extended position, and it can not be returned from this position by rotation of the spindle, as the spindle is dogged by the lug 17. Hence before the door can be opened, it is necessary to retract the secondary latch bolt by means of the actuator, and this can be retracted manually or it may be retracted by operation of the key actuated mechanism.

In my co-pending application heretofore referred to, two spindles were employed, an inner and an outer spindle, and while two latch bolts were employed only the outer spindle would be dogged when the two latch bolts assumed projected position. In this instance there is only one spindle, and this is dogged when both latch bolts are projected so that neither knob can be rotated. This is a feature which is an advantage in certain instances, as it prevents a person from locking the door from the inside and then attempting to go out and close the door thereafter. That is, with both bolts projected, it would be impossible to shut the door as the secondary latch bolt will engage the edge 52 of the striker plate and prevent further closing of the door. Thus the person going out and attempting to lock the door would have to reverse the position of the turnpiece 35, or in other words retract the secondary latch bolt before going out and closing the door, and then it is only possible to lock the door from the outside. That can be accomplished by the insertion of a key and by that means rotating the actuator to assume the position shown in Fig. 3. Then the door is locked and can only be opened again by a person in possession of the proper key.

While certain features of my invention have been more or less specifically described and illustrated, I wish it understood that changes may be resorted to within the scope of the appended claims, and that the materials and finish of the several parts may be such as the experience of the manufacturer or varying conditions of use may demand.

Having thus described and illustrated my invention, what I claim and desire to secure by Letters Patent is:

1. In a lock of the character described a tubular spindle having a rollback member formed thereon, a retractor plate having a main latch bolt secured thereto, said rollback member being engageable with the retractor plate to impart a retracting movement to the retractor plate and the main latch bolt when the spindle is rotated, a second retractor plate having a secondary latch bolt secured thereto, a rotatable member within the spindle controlling the position of the secondary latch bolt and its retractor plate, a dogging member carried by said second named retractor plate, said dogging member engaging and dogging the spindle against rotation when

the secondary latch bolt is projected and assuming an undogged position when the secondary latch bolt is retracted, and rotatable and independently operable means at each end of the spindle for rotating the rotatable member within the spindle to control the position of the secondary latch bolt and the dogging member.

2. In a lock of the character described, a tubular spindle having a rollback member formed thereon, a retractor plate having a main latch bolt secured thereto, said rollback member being engageable with the retractor plate to impart a retracting movement to the retractor plate and the main latch bolt when the spindle is rotated, a second retractor plate having a secondary latch bolt secured thereto, a rotatable member within the spindle controlling the position of the secondary latch bolt and its retractor plate, a dogging member carried by said second named retractor plate, said dogging member engaging and dogging the spindle against rotation when the secondary latch bolt is projected and assuming an undogged position when the secondary latch bolt is retracted, and a turnpiece at one end of the spindle for manually imparting rotation to the rotatable member within the spindle to control the position of the secondary latch bolt and the dogging member.

3. In a door lock, a pair of latch bolts, a single spindle journaled in the lock and adapted to retract one of the latch bolts, a rotatable member within the spindle controlling the position of the other latch bolt, and independently operable means at each end of the spindle controlling the position of the rotatable member and thereby the position of the last named latch bolt.

4. In a door lock, a main and a secondary latch bolt, a single spindle for retracting the main latch bolt, a rotatable member within the spindle controlling the position of the secondary latch bolt, a dogging member, engageable with the spindle to dog the same against rotation, and means actuated by projection of the secondary latch bolt for moving the dogging member into engagement with the spindle to prevent retraction of either of the latch bolts by the spindle.

5. In a door lock, a main and a secondary latch bolt, a single spindle for retracting the main latch bolt, an outer knob secured to the outer end of the spindle, an inner knob secured on the inner end of the spindle, a rotatable member within the spindle controlling the position of the secondary latch bolt, and means actuated by projection of the secondary latch bolt for rendering both door knobs inoperative to retract either the main or the secondary latch bolt.

6. In a door lock, a main and a secondary latch bolt, a single spindle for retracting the main latch bolt, an outer knob secured to the outer end of the spindle, an inner knob secured on the inner end of the spindle, a rotatable member within the spindle controlling the position of the secondary latch bolt, means actuated by projection of the secondary latch bolt for rendering both door knobs inoperative to retract either the main or the secondary latch bolt, and means operable from either end of the spindle for rendering both knobs operable to retract the main latch bolt and for simultaneously restoring the secondary latch bolt to retracted position.

7. In a door lock, a main and a secondary latch bolt, a single spindle for retracting the main latch bolt, an outer knob secured to the outer end of the spindle, an inner knob secured

on the inner end of the spindle, a rotatable member within the spindle controlling the position of the secondary latch bolt, means actuated by projection of the secondary latch bolt for rendering both door knobs inoperative to retract either the main or the secondary latch bolt, and rotatable means operable from either end of the spindle for rendering both knobs operable to retract the main latch bolt and for simultaneously restoring the secondary latch bolt to retracted position.

8. In a door lock, a main and a secondary latch bolt, a single spindle for retracting the main latch bolt, an outer knob secured to the outer end of the spindle, an inner knob secured on the inner end of the spindle, a rotatable member within the spindle controlling the position of the secondary latch bolt, means actuated by projection of the secondary latch bolt for rendering both door knobs inoperative to retract either the main or the secondary latch bolt, and rotatable means operable from one end of the spindle for rendering both knobs operable to retract the main latch bolt and for simultaneously restoring the secondary latch bolt to retracted position.

9. In a door lock, a main and a secondary latch bolt, a single spindle for retracting the main latch bolt, an outer knob secured to the outer end of the spindle, an inner knob secured on the inner end of the spindle, a rotatable member within the spindle controlling the position of the secondary latch bolt, a dogging member engageable with the spindle to render the spindle and both knobs inoperative to retract the main latch bolt, said dogging member being operable in unison with the secondary latch bolt and assuming an undogged position when the secondary latch bolt is retracted and a dogging position when said latch bolt is projected, and a manually operable rotatable member in the inner end of the spindle for retracting the secondary latch bolt and for simultaneously undogging the spindle to permit retraction of the main latch bolt by either knob.

10. In a door lock, a main latch bolt having a bevelled outer face, a secondary latch bolt channel shaped in cross section and embracing the main latch bolt to cover the bevelled face of said main latch bolt when both latch bolts are projected, a retractor on the main latch bolt, a single spindle, a rollback member on said spindle engageable with the retractor to retract the main latch bolt, a retractor on the secondary latch

bolt, a rotatable bar within the single spindle, a rollback member on said bar engageable with the retractor on the secondary latch bolt to retract the same, spring means normally tending to project both latch bolts, and manually actuated means for imparting rotation to the rotatable bar to control the position of the secondary latch bolt.

11. In a door lock, a main latch bolt having a bevelled outer face, a secondary latch bolt channel shaped in cross section and embracing the main latch bolt to cover the bevelled face of said main latch bolt when both latch bolts are projected, a retractor on the main latch bolt, a single spindle, a rollback member on said spindle engageable with the retractor to retract the main latch bolt, a retractor on the secondary latch bolt, a rotatable bar within the single spindle, a rollback member on said bar engageable with the retractor on the secondary latch bolt to retract the same, spring means normally tending to project both latch bolts, manually actuated means for imparting rotation to the rotatable bar to control the position of the secondary latch bolt, and a dogging member actuated by movement of the secondary latch bolt to render the single spindle either operative or inoperative.

12. In a door lock, a main latch bolt having a bevelled outer face, a secondary latch bolt channel shaped in cross section and embracing the main latch bolt to cover the bevelled face of said main latch bolt when both latch bolts are projected, a retractor on the main latch bolt, a single spindle, a rollback member on said spindle engageable with the retractor to retract the main latch bolt, a retractor on the secondary latch bolt, a rotatable bar within the single spindle, a rollback member on said bar engageable with the retractor on the secondary latch bolt to retract the same, spring means normally tending to project both latch bolts, manually actuated means for imparting rotation to the rotatable bar to control the position of the secondary latch bolt, and a dog carried by the retractor of the secondary latch bolt, said dog engaging and dogging the single spindle against rotation when the secondary latch bolt is projected and undogging said spindle when the secondary latch bolt is retracted.

WALTER R. SCHLAGE.
